(57) **CLAIM**

I claim the ornamental design for a goblet, as shown and described.

DESCRIPTION

FIG. 1 is a perspective view of a goblet showing my new design;

FIG. 2 is a front elevational view thereof; the rear, right side, and left side elevational views being a mirror image thereof;

FIG. 3 is a top plan view thereof;

FIG. 4 is a bottom plan view thereof; and,

FIG. 5 is a cross section view showing a section taken along line 5-5 of FIG. 2.
